DESIGN FOR A SHEET OF WRITING PAPER

Sara Little, New York, N. Y., assignor to Associated Card and Stationery Company, a firm

Application April 26, 1946, Serial No. 128,984

Term of patent 3½ years

(Cl. D59—14)

To all whom it may concern:

Be it known that I, Sara Little, a citizen of the United States and a resident of New York city, county and State of New York, have invented a new, original, and ornamental Design for a Sheet of Writing Paper, of which the following is a specification, reference being had to the accompanying drawing, forming part thereof.

Figure 1 is a perspective view of a sheet of writing paper shown in its normal folded condition, and showing my new design;

I claim:

The ornamental design for a sheet of writing paper, substantially as shown.

SARA LITTLE.
